UNITED STATES PATENT OFFICE.

CARL G. OLSON, OF CHICAGO, ILLINOIS, ASSIGNOR TO ILLINOIS TOOL WORKS, OF CHICAGO, ILLINOIS, A CORPORATION OF ILLINOIS.

GRINDING MACHINE.

Application filed August 14, 1922. Serial No. 581,590.

My invention relates to grinding machines, particularly for grinding or truing the teeth of gear wheels, and the object of the invention is to produce a practical and comprehensive machine capable of truing gears by means of an abrasive helicoid. This general object is accomplished by employing various novel mechanical expedients, and by constructing and grouping the elements in a manner which will be explained in detail as the description proceeds. In other words, I have produced a new organization in which various new elements and combinations of elements have been made to cooperate to accomplish the general purpose in hand. In addition to the action as a grinder, it is my purpose to produce mechanism by which the abrasive helicoid may be trued without removing it from the machine. I accomplish my objects by the mechanism illustrated in the accompanying drawings in which

Figure 1 is a front elevation of the complete machine.

Figure 2 is an end elevation looking toward the left in Figure 1.

Figure 3 is an enlarged plan view of the grinding wheel and associated parts.

Figure 4 is a sectional elevation on the line 4—4, Figure 1.

Figure 5 is a sectional elevation on the line 5—5, Figure 1.

Figure 6 is a plan section taken on the line 6—6 of Figure 2.

Figure 7 is a developed sectional elevation taken on the irregular line 7—7 Figure 5.

Figure 8 is a sectional detail taken on the line 8—8 Figure 3. This shows the yieldable tail stock.

Figure 9 is a detail view looking obliquely downward toward the right as indicated by the arrow at 9, Figure 2. Certain parts are broken away to reveal the internal construction.

Figure 10 is a sectional view on the line 10—10, Figure 7. This deals with the clutch comprising part of the feed screw connection.

Figure 11 is a sectional view of the clutch on the line 11—11, Figure 10.

Like numerals denote like parts throughout the several views.

The grinding wheel 1 is in the form of an abrasive helicoid and is secured to a hub 2

keyed or otherwise fastened to the grinder spindle 4. For reasons presently to be explained the spindle stands in oblique position with reference to the floor, as best illustrated in Figures 2 and 4. It is journaled in a bushing 6 mounted in the main frame 8 of the machine and dust is excluded from the bearing by means of a cap 10. The bearing is further protected by means of a trap shown in detail in the upper portion of Figure 4. The hub 2 is made chambered and a flange 12 which is bolted or otherwise secured to the main frame projects up into the body of the hub. The trap has an annular base portion 14 and at the flanged periphery of said base portion a cylindrical guard 16 is formed which rises to a point considerably above the upper surface of the grinding wheel. At one portion said guard has a gap 18 through which the grinding wheel projects to enable it to reach the gear 20, which constitutes the work. Thus it may be considered that the grinding helicoid and its supporting hub are telescopically mounted in an annular well or housing. The arrangement is illustrated in Figures 1, 3 and elsewhere.

The grinder spindle 4, previously mentioned, is supported at the foot by a step bearing illustrated in section in Figure 4. The lower end of the spindle is hollowed and contains a wearing pin 21 of hard metal which rests upon a ball 22. Beneath the ball is a wearing plate 24 which rests upon the top of a post 26 which projects up into the chambered lower end of the spindle. The result of the oblique mounting of the grinder spindle is that the weight and thrust are divided among the separate and different kinds of bearings and hence the amount of wear is minimized and the machine remains true for a long period.

At the lower end the post 26 has an integral adjusting screw 28 which works in an internally threaded bushing or nut 30 supported in a stationary bracket 32 which forms a part of the main frame 8. By rotating this adjusting screw in the bushing the spindle may be raised or lowered in its bearing 6. By thus making it possible to longitudinally adjust the grinder spindle, it becomes possible to bring different portions of the abrasive thread on the grinding

wheel into the field of action. Consequently, if a wide face grinding wheel is employed, that is, one having an extra long thread, it may be made to last a long time without redressing.

The set screw 28 has an integral flange 34 which is countersunk in an indexing disc 36. The two are rigidly held together by studs 38. The indexing disc is notched at its periphery for engagement with a stationary detent 40 shown near the bottom of Figure 1. This detent is transversely slotted to accommodate binding screws 42 which screw into the main frame 8. It will be evident that the disc and adjusting screw may be fixed in any desired angular position by means of the detent 40.

At certain times it is desirable to have the grinder spindle 4 and adjusting screw 28 rotate in unison. For this purpose I have provided a flanged sleeve 43 which is rigidly secured to the spindle and is apertured to receive a locking pin 44 shown in dotted lines near the lower end of Figure 4. It will be understood that during the normal operation of the machine, that is, when the grinder is acting upon the work 20, said locking pin will be absent. The lead of the screw 28 is the same as the lead of the helical thread on the grinder 1, and consequently when the grinder spindle and screw rotate in unison the grinder shaft will have a longitudinal movement corresponding to the lead of the thread on the grinder. This makes it possible to employ the truing devices which are mounted upon the machine, and will be hereinafter described. It will thus be evident that screw 28 performs the dual function of an adjusting screw or a resetting screw at times, and the function of a lead screw or master screw at other times. It performs the function of a lead screw at the time when it rotates in unison with the grinder spindle for the purpose of dressing the grinder.

The grinder spindle 4 is rotated by means of a bevel gear 46 which encircles and is rigidly secured to a sleeve 48, which is splined to the spindle. Said sleeve bears in a sleeve 50 which is mounted in the main frame 8. Bevel gear 46 is driven by means of a bevel gear 52. Bevel gear 52 is rigidly fastened to a shaft 54 best illustrated in Figure 7. Said shaft is supported in two stationary bearings 56 and during normal operation is driven by a pulley 58 which is keyed or otherwise rigidly secured to it. Said pulley is driven by means of a belt 60 or other suitable source of power. On certain occasions said shaft is driven by a worm wheel 62 which is engaged by a worm 64 secured to a shaft 66 journaled in a cylindrical housing 68. This forms part of what may be termed the transmission. At its lower end said shaft has a worm wheel 70

which is engaged by a worm 72 secured to the shaft 74 of an electric motor 76 or other source of power. These parts are clearly shown in Figures 5 and 7. Worm 72 is enclosed in a housing 78 which is cylindrical and is integral with the housing 68. Housing 78 is adapted to rock in a bracket 80 mounted upon a stationary platform 82 which also carries the motor. The purpose in having the housing 78 rockable is to make it possible to swing the worm 64 into and out of engagement with the worm wheel 62. This movement of the worm is accomplished by control mechanism, a portion of which is shown in Figure 5. A pin 84 is carried by housing 68 and forms a point of pivotal connection to a link 86. Said link is connected by a pin 88 to a crank 90 which is shown in full lines at the left side of Figure 6. Said crank is rigidly secured to a rock shaft 92 enclosed in a housing 94 and operated by means of a handle 96 which is rigidly secured to shaft 92. Thus by operating the handle the worm 64 may be thrown into and out of engagement with the worm wheel 62.

I will now describe the mechanism which drives the work spindle 98 on which the work 20 is mounted. Refer particularly to Figure 7. Rigidly secured to shaft 54 is a pinion 100 which meshes with a gear wheel 102 mounted upon a stationary shaft 104. Rigidly connected to gear wheel 102 is a gear wheel 106 which meshes with a gear wheel 108 rigidly fastened to a shaft 110. This shaft is journaled in two sleeves 112 which are mounted in the main frame 8. Said shaft is encircled by a hollow cylindrical elongated pinion 114 which meshes with and drives a gear wheel 116 keyed or otherwise rigidly secured to shaft 118. This drives the work spindle 98 in the manner hereinafter explained. In order to produce angular adjustment of pinion 114 upon shaft 100, said pinion has an oblique slot 120 in which works a pin 122 which projects laterally from a plunger 124, which slides within a suitable counterbore in shaft 110. Shaft 110 has a slot 126 which is oblique to the shaft and also oblique to slot 120. Pin 122 projects through both of these slots and it will be evident that by moving pin 122 in one direction or the other lengthwise of shaft 110 the angular position of pinion 114 on said shaft will be varied. A similar slotted pin construction is duplicated on the opposite side of the shaft as will be apparent from an examination of Figure 6. A helical compression spring 128 is mounted within shaft 110 and exerts a constant outward pressure on shaft 124 which is controlled by means of an adjusting screw 130 which screws in a threaded plate 132 secured to the main frame 8. An anti-friction ball 134 is interposed between the inner ends of said screw 130 and the outer end of

plunger 124. A lock nut 136 is provided for holding the adjusting screw 130 in proper position. The thrust of the spring 128 is absorbed by a thrust-bearing 138 which has a stationary abutment in the machine. The mechanism just described constitutes a slot and pin mechanism for adjusting the wide-face pinion 114 angularly with respect to the driving train of gears 100, 102, 106, and 108. This adjusts the work angularly and makes it possible to bring the teeth on the work into correct cooperative relation with the abrasive thread on the grinding wheel.

Shaft 118, previously mentioned, is both rotatable and slideable in a rocking frame 139 and has a taper socket 140 which receives a taper pin 142, the latter constituting a center for supporting the work spindle 98. Shaft 118 therefore constitutes a rotatable and slideable chuck. A collapsible dust guard 144 surrounds the bearing and excludes dust therefrom. This is shown in section in Figure 7.

The longitudinal movement of shaft 118 is produced by a feed screw and clutch which is shown in section at the upper left corner of Figure 7, and also in Figures 10 and 11. An internally threaded nut 146 is rotatable but longitudinally fixed in the rocking frame 139. Within this nut works the feed screw 148 which is hollow and slidably supports a clutch pin 150. At its inner end said pin has a block 152 adapted to enter a socket 154 in the outer end of shaft 115. By moving the pin to acting position shown in Figure 7 the feed screw and shaft will rotate in unison and the shaft and work will be fed in an axial direction. By pulling outward on the pin the block 152 will be withdrawn from the socket and the shaft 118 may rotate independently of the feed screw. Nut 146 is stationary in the normal operation of the machine, that is when the shaft 118 is feeding forward. The shaft may be returned to the initial position shown in Figure 7 by means of a pulley 156 which is rigidly fastened to nut 146. A belt 158 drives pulley 156 and is driven by a pulley 160 fastened to the motor shaft 74.

Now to refer to the tail stock which supports the opposite end of the work spindle 98. This mechanism is shown in section in Figure 8, and is so constructed as to permit the longitudinal feeding of the work spindle. A center 162 supports the end of the spindle and is yieldingly pressed toward it by a helical compression spring 164, which is backed up by a plate 166 adjustably carried on rods 168. By preference the center is chambered to receive the forward end of the spring. Said center is slidably mounted in a sleeve 170 secured to an enclosing sleeve 172 adapted to be clamped in the split-bearing 174. A dust cap 176 is secured to center 162 and telescopically enters an annular recess 108

in sleeves 170, 172. Thus I have provided a yielding tail stock and a dust guard for protecting the sliding center 162.

Shaft 118 is, as previously stated, mounted in a rocking frame 139, the purpose being to adjust the work bodily toward and from the grinding wheel. The mounting and means for controlling said frame are best illustrated in Figures 5 and 7. Said frame is irregular in form as shown in Figure 7 but has a semi-circular portion for housing the lower half of gear 116. The frame is mounted upon sleeves 112 which are adapted to oscillate in the main frame 8. The angular position of the frame is controlled by a link 178 which is pivotally connected at one end to the frame and at the other end to a block 180 slidably mounted on the main frame so as to move in a direction oblique to the horizon as shown in Figure 5. The position of this block on the frame is controlled by an adjusting screw 182 controlled by a hand wheel 184. Said screw has a rotatable but non-shiftable bearing in the block 186 mounted on the main frame. Thus it will be evident that by properly manipulating the hand wheel 184 the shaft 118 and work arbor 98 may move the work 20 bodily toward and from the grinding wheel.

I will now describe the mechanism provided for truing the grinding wheel. Referring to Figure 9 it will be observed that two spindles 188 are rotatably mounted in sleeves 190 clamped in bearings 192. Each is provided with a disc 194 provided with a grinding point 196. These operate upon the principle set forth in my copending application filed October 31, 1921, Serial No. 511,795. The split bearing or clamp 192 is mounted upon a bar 198 which has a stud 200 projecting from it and adapted to be clamped in the split bearing 202, the latter being mounted upon a turret or indexing table 204. This has concentric slots 206 adapted to accommodate clamping studs 208 which rise from the carriage 210. Said carriage is slidably mounted upon a cross carriage 212 which is adjustable upon the main frame 8. The position of carriage 210 is controlled by hand wheel 214 and the position of cross carriage 212 upon the main frame is controlled by hand wheel 216. These parts are shown, for example, in Figures 2 and 3. The spindles 188 are rotated by sheaves 218 driven by belts 220. These belts pass over idler sheaves 222 which are mounted on a bar 224 carried by a bracket 226. Said bracket is secured to a bracket 228 which supports the tail stock and is fastened to rocking frame 139. The belts 220 are driven by sheaves 230 shown at the bottom of Figures 1, 2 and elsewhere. Said driving sheaves are driven by the motor shaft 74 previously mentioned. As the bar 198 occupies a fixed position under ordinary conditions and the idlers 222

- are mounted so as to rock in unison with the rocking frame 139, it follows from the construction best illustrated in Figure 2 that the rocking movement of the frame 139 will cause sheave 222 to tighten or loosen the belts 220. The arrangement is such that the belts become tight and drive the truing wheels or dressing points 196 when the work arbor 98 is swung away from the grinding wheel 1. 10 In other words, the same movement that moves the work away from the grinding wheel tightens the belt so that the dressing points will commence to operate. Consequently the rocking frame 139 may be regarded, among other things, as a belt tightener. 15

Operation: Let it be assumed that the parts are adjusted to the relative position shown in Figure 4 with the grinding wheel 1 in engagement with the work 20. As mentioned, the grinding wheel is an abrasive helicoid whose function is to grind the teeth of the gear wheel 20, operating somewhat after the manner of a hub, but grinding the surface of the teeth rather than generating them. At the same time that the grinding wheel is rotated by the spindle 4, the work arbor 98 and shaft 118 will feed the work in an axial direction. The gear wheel 116, being in mesh with the wide-face pinion 114, will at the same time rotate the work about its axis to enable the teeth to present themselves successively to the action of the grinding helicoid. This is the normal operation of the machine. When the grinding action has been completed and it is desired to return the work arbor 98 and shaft 118 axially to the initial position the grinder spindle is brought to rest by stopping the belt 60, thus bringing the main drive shaft 54 to rest. The motor 76 is then started, which causes pulley 156 to rotate the feed nut 146 in a direction to retract the feed screw 148 and move it toward the left of Figure 7. 40 This action is continued until the work arbor has been returned to initial position. This constitutes the normal return movement of the work arbor. 45

If, now, it is desired to true or dress the helicoid on the grinding wheel the feed screw 148 is thrown out of action by withdrawing clutch pin 150. The dressing or truing wheels 194 are brought into acting position by manipulating the adjusting screws 214, 216, (see Figures 2, 3 and 9). The worm 64 is now thrown into gear with the worm wheel 62 by manipulating the handle 96 (see for example Figures 6 and 7). The operator then moves the rocking frame 139 about its axis to bring the work 20 out of engagement with the grinding wheel 1. The operator also inserts locking pin 44 so that when the grinding wheel is rotated it will be fed axially relatively to the grinding wheels or discs 194. The motor 76 is now

started, and as the movement of the rocking frame 139 has caused the sheaves 222 to tighten the belts 220, the grinding points will be caused to rotate and correct the form of the helicoidal thread on the grinding wheel. Thus in a single machine I have provided means for both using and truing the abrasive helicoid and have produced a very complete and practical machine for the grinding of the teeth of gear wheels and the like. 70

Having thus described my invention what I claim as new and desire to secure by Letters Patent is:

1. A grinding machine having a work spindle, a grinder spindle, means for rotating them continuously in timed relation, and a screw movable at all times in unison with the grinder spindle in an axial direction but angularly independent of said grinder spindle except when connected to it, means for adjusting at times the angular position of said screw to adjust the grinder spindle a predetermined amount in an axial direction to a new position, and means for connecting at other times the screw to the grinder spindle for causing the latter to travel axially. 80

2. A grinding machine having a work spindle, a grinder spindle, means for rotating said spindles continuously in timed relation, an adjusting screw separate from the grinder spindle and arranged longitudinally of it and making end contact with it, means for holding at times the adjusting screw in predetermined angular positions, and means for connecting at other times the screw to the grinder spindle for causing the latter to travel axially. 95

3. A grinding machine having a work spindle, a grinder spindle arranged transversely to it, means for rotating said spindles in timed relation, an adjusting screw arranged longitudinally of the grinder spindle and forming a step bearing for it, and means for connecting the grinder spindle to said screw for causing the two to rotate in unison for causing the grinder spindle to travel longitudinally. 100

4. A grinding machine having a work spindle, a grinder spindle arranged transversely to it and arranged obliquely to the horizon, said grinder spindle having a step bearing at the lower end and having a circumferential bearing above the step bearing, an adjusting screw arranged longitudinally of the grinder spindle and forming a part of the step bearing, and means for disconnectably connecting the grinder spindle and the adjusting screw whereby the two may rotate independently at times and simultaneously at other times. 110

5. A grinding machine having a grinder spindle, a grinder having a helicoidal abrasive thread, a work spindle, means for rotating said spindles in timed relation, a rock- 120

- 5 ing frame wherein the work spindle is journaled, means for rocking said frame about its pivot for locating the work spindle at the proper distance from the grinding wheel said means being adapted to hold said frame in the position to which it is adjusted.
6. A grinding machine having a main frame, a grinder spindle, a grinder provided with a helicoidal abrasive thread, a 10 work spindle means for rotating said spindle in timed relation, a rocking frame pivoted on the main frame and supporting the work spindle, a block slideable on the main frame, an adjusting screw for controlling 15 the position of the block, and connections between the block and the rocking frame for controlling the position of the rocking frame about its pivot, and thereby controlling the distance of the work spindle from 20 the center of the grinding wheel.
7. A machine for grinding involute gear teeth, having a rotatable, and longitudinally slideable work spindle, a power device, transmission gears for driving said work spindle 25 and at the same time permitting it to move longitudinally, one of said transmission gears being wide faced, a grinding wheel having an abrasive helicoid, a grinder spindle for rotating said grinding wheel, means 30 for rotating the two spindles in timed relation to the pitch of the helicoid and the pitch of the gear and means for simultaneously feeding the work spindle longitudinally.
- 35 8. A grinding machine having a rotatable and longitudinally slideable work spindle, a power device, transmission gears for driving said work spindle and at the same time permitting it to be fed longitudinally, a 40 grinding wheel having an abrasive helicoid, a grinder spindle for rotating said grinding wheel, means for rotating the two spindles in timed relation, means for simultaneously feeding the work spindle longitudinally, and means for angularly adjusting 45 the work spindle with reference to the transmission gears.
9. A grinding machine having a work spindle, a power device, transmission gearing for transmitting power from the power device to the work spindle, said transmission gearing including an intermediate shaft having a pin projecting therefrom, an intermediate pinion having an oblique slot 55 through which the pin projects, and means for causing relative movement between the pin and the pinion in an axial direction to thereby angularly adjust the pinion relative to the intermediate shaft.
- 60 10. A grinding machine having a work spindle, a power device, transmission gear-
- ing for transmitting power from the power device to the work spindle, said transmission gearing including an intermediate shaft having an oblique slot, an intermediate, wide 65 faced pinion cylindrically bored to fit over said shaft, said pinion having an oblique slot arranged at a different angle from the first mentioned slot, a plunger slideable within the intermediate shaft, a pin secured to the 70 plunger and projecting out through the two slots, and means for controlling the position of the plunger to thereby angularly control the position of the pinion relatively to the intermediate shaft. 75
11. A grinding machine having a power device, a work spindle, a grinder spindle, an intermediate shaft, gear trains for driving said spindles, and a transmission adapted to connect and disconnect the intermediate 80 shaft from the power device, said transmission including a worm wheel on the intermediate shaft, a worm driven by the power device and adapted to swing into and out of engagement with said worm wheel, and 85 means for swinging the worm into and out of engagement with said worm wheel.
12. A grinding machine having a grinding wheel, a grinder spindle, a truing wheel for dressing said grinding wheel at times, a sheave for rotating said truing wheel, a belt for driving said sheave, a work spindle, means for rotating said spindles in timed relation, a rocking frame wherein the work spindle is journaled, the movement of the 90 rocking frame about its axis moving the work spindle towards and from the grinder, and an idler sheave mounted on said rocking frame for tightening the belt and thereby causing the truing wheel to rotate when 95 the work spindle moves away from the grinder spindle. 100
13. A grinding machine having a work spindle, a grinder spindle arranged transversely to it, means for rotating said spindles in timed relation, a screw in axial alignment with said grinder spindle to serve the dual function of adjusting screw and lead screw, the grinder spindle having a step bearing upon said screw, and also a journal bearing thereon, a nut in which said screw works for causing longitudinal movement of said screw, means for holding said screw in various angular positions to obtain new locations, axially, of said grinder spindle, and other means for coupling the work spindle to the screw for causing them to rotate in unison and the screw, consequently, to 110 function as a lead screw. 115
- In witness whereof, I have hereunto subscribed my name.
- CARL G. OLSON. 120
